UNITED STATES PATENT OFFICE.

JAMES C. DAWSON, OF WEBSTER GROVES, MISSOURI.

BINDING-STRIP FOR LOOSE-LEAF LEDGERS AND PROCESS OF COVERING SAME.

1,329,379.

Specification of Letters Patent. Patented Feb. 3, 1920.

Application filed May 17, 1919. Serial No. 297,917.

To all whom it may concern:

Be it known that I, JAMES C. DAWSON, a citizen of the United States, and resident of Webster Groves, county of St. Louis, and 5 State of Missouri, have invented certain new and useful Improvements in Binding-Strips for Loose - Leaf Ledgers and Processes of Covering the Same, of which the following is a specification, and which are illustrated 10 in the accompanying drawings, forming a part thereof.

The invention relates to loose leaf ledgers and has for its object an improved method for readily covering the apertured and post 15 carrying strips with the usual canvas and the provision of a new structure which makes possible the carrying out of the method.

In the accompanying drawings:

20 Figure 1 is a sectional view showing a pair of the binding strips and one of the associated posts, the post being partly in elevation,

25 Fig. 2 is a transverse section of the post carrying binding strip without the covering therefor and with the socket plug omitted.

Fig. 3 is similar to Fig. 2, but shows the socket plug in place,

30 Fig. 4 is similar to Fig. 3, but shows the canvas cover placed about the binding strip, the said canvas cover being as yet without apertures in line with the filing posts,

35 Fig. 5 is a similar view of the completed binding strip ready for the reception of the filing post,

Fig. 6 is a transverse section of the adjustable binding strip without its cover,

40 Fig. 7 is a plan view of the binding strip of Fig. 6 with the covering laid over the same, not yet perforated,

Fig. 8 is a transverse sectional view taken on the line 8—8 of Fig. 7 and showing the perforating implement in place,

45 Fig. 9 is a view corresponding to Fig. 7 with the covering perforated,

Fig. 10 is a transverse section illustrating the manner of perforating the covering,

Fig. 11 is a perspective view of the socket plug designed to be associated with the post 50 carrying binding strip as in Figs. 1, 3, 4, and 5, and

Fig. 12 is a perspective view of the cutting implement employed for perforating the covering of the adjustable binding strip.

55 In the drawings Fig. 1 illustrates the two binding strips 15, 16, such as are usually em-

bodied in a loose leaf ledger, each of said binding strips being provided with a covering, as 17. This covering is preferably made of canvas and is placed upon the strip 60 to improve the appearance of the same and may be used as a means of attachment of the ledger covers (not shown). The present invention has to do with the improved method and structure which permit the application 65 of the covering as 17, without threading the same over the posts, as 27, and in such a manner as to produce a neat appearance.

In carrying out the invention there is provided a plug which may take the form of 70 the socketed plug illustrated at 18 in Fig. 11, or the solid plug illustrated at 19 in Fig. 12. The characteristic common to both of the said forms of plug is the presence of a cutting edge 20 which comprises an extension 75 of the periphery of the plug in conjunction with a recessed end, as 21, thereof. In the case of the socket plug 18, one of these plugs is placed in each of the perforations, as 22, of the post carrying binding strip, as 80 15, one end of the plug being preferably provided with a reduced portion, as 23. After being placed in the strip in the manner shown in Fig. 3, the reduced portion 23 has its end upset, as indicated at 24, to 85 retain the plug permanently in place. As illustrated in Figs. 3, 4 and 5, the cutting edge 20 of the plug 18 projects beyond the surface of the binding strip, as at 25, the amount of the projection being preferably 90 substantially equal to the thickness of the subsequently applied covering, as 17. The socket, as 26 of plug 18, is screw threaded for the reception of the threaded end of one 95 of the filing posts, as 27, of the ledger.

When the socket plug 18 has been placed in position, as in Fig. 3, and covering 17 has been applied about the strip and over the ends of the plug, in the manner illustrated in Fig. 4, a sharp blow as with a 105 hammer (not shown) upon the covering 17, in line with the cutting edge 20 of the plug, will cause the said cutting edge to force its way through the covering and the covering will be forced down about the extending 100 cutting edge into the position illustrated in Fig. 5. As the cutting edge is now substantially flush with the face of the finished covering, it will not be objectionable and it will furthermore have been somewhat 110 dulled by the hammer blow just described.

For the purpose of covering strip 16 which

must be finished with a clear perforation for the reception of the filing post, as 27, of the ledger, the solid plug, as 19, having a cutting edge 20 at each end, is desirably provided, such plug being purely an implement. As shown, the plug 19 is of such length that when placed in an aperture of the strip 16, as indicated in Fig. 8, it will project from both surfaces of the strip. 5 With the implement in place, covering 17 is placed over the strip and implement, as illustrated in Fig. 8, in exactly the same manner as in the case of the binding strip 15, Fig. 4. In the present instance the strip 16 should now be laid on a bed of material as 29, such as lead, copper, hard wood or other substance softer than the plug 19 and a piece 28 of like soft material is placed over the strip 16 in line with the plug 19. 10 Force, if applied to 28, as in Fig. 10, will cause the cutting edge upon each end of implement 19, to perforate the covering material exactly as in the structure of Fig. 5, at the same time forcing the material down into 15 contact with the strip around and closely adjacent to the periphery of the projecting edge of the implement. After the covering has been cut, as illustrated in Fig. 10, plug 19 is removed through one of the perforations thus formed in the said covering and strip 16, with its covering in place, may be used in the manner indicated in Fig. 1.

I claim as my invention:

1. The process of covering an apertured article which comprises placing a plug having a peripheral cutting edge at the outer end of the same in the aperture of the article, placing the covering upon the article and over the plug, applying force to said covering against said cutting edge whereby said covering will be perforated opposite the aperture in said article. 35

2. The process of covering an apertured article which comprises placing a plug having a peripheral cutting edge at the outer end of the same in the aperture of the article, said cutting edge projecting above the surface of said article a distance substantially equal to the thickness of the covering, placing the covering upon the article and over the plug and applying force to said covering against the cutting edge whereby said covering will be perforated to correspond with the aperture of said article. 45

3. The process of covering an apertured article which comprises placing a plug in the aperture of the article, such plug having at each end a continuous cutting edge constituting a longitudinal extension of its periphery, said cutting edges projecting at 55 each side of the article a distance substan-

tially equal to the thickness of the covering, applying the covering about the article and over the plugs, and applying force to the covering against the cutting edges whereby 65 the covering is perforated by the cutting edges, and removing the plug.

4. The process of covering an apertured article which comprises placing a plug having a continuous peripheral cutting edge at 70 the outer end of the same in the aperture of the article, said cutting edge projecting from the surface of the article, placing the covering over the article and cutting edge, applying an implement of softer material than 75 the plug forcefully to said covering over said cutting edge, whereby said edge will be forced through the material and into the implement and the covering will be pressed into contact with the article at about the perforation thus formed. 80

5. A loose leaf ledger comprising an apertured binding strip, a plug in the aperture of the binding strip, said plug having an upstanding cutting edge projecting above the 85 surface of said strip, and a covering for said strip perforated in line with the strip aperture, the surface of said covering being substantially flush with the said cutting edge. 90

6. A loose leaf ledger comprising an apertured binding strip, a socketed plug fixed in the aperture of the strip, the outer end of the plug being substantially flush with the surface of the strip, and a post removably secured in the socket of the plug. 95

7. A loose leaf ledger comprising a binding strip having an opening, a plug seated in said opening, said plug having an upstanding cutting edge and a screw-threaded socket, a post having a reduced screw-threaded end seated in said socket, and a covering on said binding strip closely surrounding and substantially flush with said cutting edge. 100

8. The method of making the post carrying binding strips of loose leaf ledgers, and the like which consists in providing the strip with a post receiving socket, applying a covering of canvas or the like to the strip over the said socket, perforating the covering in line with the said socket and entering a filing post in the said socket. 105

9. A post carrying binding strip for loose leaf ledgers and the like comprising, in combination, an apertured strip, a socketed plug fixed in the aperture of the strip, a covering of canvas or the like extending about the strip and over the plug, the said covering being apertured in line with the plug socket and a filing post removably held in the plug 110 socket. 115

JAMES C. DAWSON.
